UNITED STATES PATENT OFFICE.

WILLIAM H. DENNEY, OF SOUTH ORANGE, NEW JERSEY.

VANITY CASE.

Application filed December 6, 1922. Serial No. 605,238.

To all whom it may concern:

Be it known that I, WILLIAM H. DENNEY, a citizen of the United States, and a resident of South Orange, in the county of Essex and State of New Jersey, have invented a new and Improved Vanity Case, of which the following is a full, clear, and exact description.

This invention relates to containers and 10 contemplates more particularly an improvement in vanity cases which are employed as combined containers or packages for rouge and face powder compacts.

In the common forms of twin containers 15 for rouge and face powder compacts which are now in general use and on the market, the same are usually of a circular form consisting of a cylindrical body divided transversely into separate compartments for the 20 rouge compact and the face powder compact. Under this construction access is gained to the separate compartments either by lifting up one of the compartments which covers the other or by providing a hinged cover at 25 opposite ends, both of which forms are more or less inconvenient to the user due to the fact that access cannot be gained to the both compartments simultaneously. In the type which is provided with the hinged cover at 30 its opposite ends, the expense of providing two mirrors is entailed. In the other oblong or non-circular forms of compact containers which have the rouge and face powder compartments alongside of each 35 other, the vanity case must be small enough for conveniently fitting the palm of a woman's hand and when such forms are used, it has been found that the compacts contained therein are too small to be of 40 practical value. When non-circular or oblong types of cases are made sufficiently large to hold the regulation sized compacts the bulk of the case containing them is too 45 large for convenient handling.

It is therefore the principal object of the present invention to overcome the above recited objections and disadvantages by producing a twin compact vanity case or container which while requiring only a single 50 hinged cover and mirror and retaining the convenient circular form to hold the regulation size of compacts permits the gaining

of access to both compartments simultaneously.

Briefly stated the invention accomplishes 55 the foregoing objects by constructing a twin compact container or vanity case of the convenient circular type provided with a single regulation hinged cover and a single mirror, which cover when opened discloses an upper 60 compartment in which the regulation size of compact is arranged with an applicator or puff therefor, the said upper compartment being so connected with the body as to permit of its lateral swinging movement to 65 uncover a lower compartment in which a second compact with its applicator or puff is located whereby the user may simultaneously have access to both compacts while employing the same mirror for the application 70 of the contents.

The invention further contemplates a vanity case which is extremely simple in its construction and mode of operation, inexpensive to manufacture and produce and 75 one which is highly efficient in its purpose.

With the above recited and other objects in view, the invention resides in the novel construction set forth in the following specification, particularly pointed out in the 80 appended claims and illustrated in the accompanying drawing, it being understood that the right is reserved to embodiments other than those actually illustrated herein to the full extent indicated by the general 85 meaning of the terms in which the claims are expressed.

In the drawing—

Figure 1 is a perspective view illustrating a vanity case constructed in accordance 90 with the invention with the cover and upper compartment opened.

Fig. 2 is a similar view of the case in closed condition.

Fig. 3 is an enlarged sectional view taken 95 approximately on the line 3—3 of Fig. 2.

Fig. 4 is a fragmentary detail sectional view taken approximately on the line 4—4 of Fig. 2.

Fig. 5 is a fragmentary detail sectional 100 view taken approximately on the line 5—5 of Fig. 1.

Referring to the drawing by characters of reference, 10 designates the substantially

cylindrical body of the case which is closed at its lower end by a bottom 11. The body 10 is cut away for approximately one-half of its circumference to a distance from its upper end substantially two-thirds of the height thereof, while the upper edge of the cutaway portion is turned inwardly to provide a substantially semi-circular flange or shelf 12. A section consisting of a substantially semi-circular wall 13 and a disk-like bottom 14 is hingedly attached as at 15 to the body 10 and constitutes a tray or compartment for the face powder compact. The end of the wall 13 opposite to the hingedly connected end is offset inwardly as at 16 and is provided with a circumferential outwardly projecting bead 17 which is designed to be received in a complementary circumferential groove 19 formed in the inner periphery of the body 10 for the purpose of locking the container or compartment section against relative axial movement when said section is in closed relation to the body 10. When in closed position the inwardly offset end 16 lies snugly within the meeting end of the body and the semi-circular wall 13 of the section completes with the body 10 a circular upper end over which a hinged cover 18 is adapted to fit. The lower end of the body 10 and the bottom 11 constitute a compartment for a rouge compact which when the powder tray or compartment is closed underlies the same and which when said powder compartment is opened is exposed thereby sufficiently to permit the user to gain access thereto as clearly illustrated in Fig. 1 of the drawing. In order to limit the opening of the powder compartment or tray which swings laterally on the hinge 15, guide grooves 19 are formed in the under side of the disk or bottom 14 and stops 20 consisting of up-struck portions of the flange or shelf 12 are received in said grooves and coact with the inner ends 21 thereof as illustrated in Fig. 5. To preclude any possibility of cutting the user, the edge of the bottom or disk 14 which lies between the opposite ends of the semi-circular wall 13 is bent upon itself as at 22. The flange or shelf 12 serves as a support for the powder compartment in its open and closed positions and during the movement of the same from one of said positions to the other.

In use and operation the user in order to gain access to the contents of the several compartments swings the cover 18 to its open position and swings the upper compartment or section to the full open position as illustrated in Fig. 1 thereby simultaneously exposing the compacts in both compartments for use. When finished, the user merely closes the upper compartment and the cover 18 which locks the upper compartment in closed position and against accidental opening as clearly illustrated in Fig. 2. By con-

structing the case in the manner heretofore set forth, it is obvious that a more convenient article of this character has been provided which at the same time eliminates the necessity of employing two mirrors as is now required by the present construction of devices of this character.

I claim:

1. A container including a body having a bottom and a flange formed with a cutout portion, and a tray comprising a bottom and a flange, said tray hinged to the body to swing laterally, the flange of the tray forming a closure for the cutout portion of the body.

2. A container including a body having a flange formed with a cutaway portion and a tray comprising a bottom and a flange, said tray hinged to the body for lateral swinging movement through the cutaway portion, the flange of the tray forming a closure for the cutaway portion of the body when the tray is in closed position, and interengageable means at the meeting edges of the flanges of the tray and body for preventing relative axial movement therebetween.

3. A container including a body having a bottom and a flange formed with a cut-out portion communicating with the upper open end of the flange, a tray comprising a bottom and a flange having hinged connection to the body for lateral swinging movement through the cut-out portion of the body, the said tray when swung inwardly defining therebeneath a container compartment and when swung outwardly serving to expose said compartment, the said flange of the tray constituting when closed a closure for the cut-out portion, and a cover hinged to the body and engageable over the flange of the body and tray when closed to hold the tray in closed position relative to the body.

4. A cosmetic container comprising a body including a bottom and an annular upstanding wall formed with a cut-out portion adjacent its upper end, an inwardly projecting flange at the lower edge of the cut-out portion, a tray comprising a bottom and an upstanding flange, said tray hinged to the body for lateral swinging movements, the flange of the tray forming a closure for the cut-out portion of the body when in closed relation thereto, and interengageable means provided respectively on the bottom of the tray and on the inwardly projecting flange of the body for limiting the outward lateral swinging movement of the tray.

5. A cosmetic container comprising a body including a bottom and an annular upstanding wall formed with a cut-out portion adjacent its upper end, an inwardly projecting flange at the lower edge of the cut-out portion, a tray comprising a bottom and an upstanding flange, said tray hinged to the

body for lateral swinging movements, the flange of the tray forming a closure for the cut-out portion of the body when in closed relation thereto, interengageable means provided respectively on the bottom of the tray and on the inwardly projecting flange of the body for limiting the outward lateral

swinging movement of the tray, and a cover hinged to the body and engageable over the upper end of the annular wall of the same 10 and the upper end of the flange of the tray for retaining said elements in closed condition.

WILLIAM H. DENNEY.
